CREAM-MILK CAN WASHING APPARATUS

Frederick W. Coffing, Danville, Ill.

Application April 16, 1936, Serial No. 74,636

10 Claims. (Cl. 141—7)

This invention relates to a washing and sterilizing device, particularly applicable for creamery and dairy use.

One object of the invention is to provide a device which has all the advantages of prior art devices and which is more economical to construct and which has certain detachable parts, whereby the same may be more readily cleaned.

Another object of the invention is to provide a device of the aforesaid character with a measuring control, whereby the amount of water supplied to a flash boiler for the formation of steam is of constant volume.

One feature of the invention consists in the simplified form of the combination can support and drain.

Another feature of the invention consists in the simplified detachable mounting thereof upon the machine frame.

A third feature of the invention is directed to the economical use of the heat, as will be more fully pointed out hereinafter.

A fourth feature of the invention consists in the measuring valve and its operative connection to the flash boiler as well as its manual control.

The full nature of the invention will be understood from the accompanying drawing and the following description and claims:

In the drawing, Fig. 1 is a front elevational view of a cream washer and sterilizer embodying the invention, parts being broken away to show other parts in detail.

Fig. 2 is a transverse sectional view thereof taken in the plane of the boiler supply control valve, the compartment cover and heating device being shown in elevation.

Fig. 3 is a top plan view of the detachable sterilizer support and drain, and its support upon the frame of the machine.

In the drawing, 10 indicates the rectangular frame of angle iron and 11 indicates four angle iron legs suitably secured thereto. Said legs below the angle iron frame-work 10 are suitably connected together as by the angle irons 12 and 13.

Mounted in the frame-work is a semi-cylindrical trough structure 14 which has soldered therein or otherwise suitably secured thereto, a semi-circular partition 15 intermediate the ends 16 and 17, forming a can washing compartment 18, and the clean hot water compartment 19.

Suitably surrounding the two compartments and depending therefrom, as shown clearly in Figs. 1 and 2, are the plate or shield portions 20,

and these terminate approximately in the plane of the bracing members 12 and 13.

Suitably supported by the brace members 12, as upon the transverse members 21, is a flash boiler 22 having a steam discharge outlet connected to a discharge pipe 23 in one end. The upper side of the flash boiler is spaced from the lower surface of the compartment 19, as shown in Figs. 1 and 2, but the two communicate as indicated at 24. Such communication is of rigid character and is suitably packed or gasketed to prevent leakage from the boiler and leakage from compartment 19.

The conduit 25 has a threaded connection with the valve body 26 and the lower flange of the valve cooperates with the packing structure to secure the entire arrangement in leakproof relation.

The valve body—see Fig. 2—is chambered as at 27 and a frusto conical valve member 28 is mounted in said chamber and has a portion 29 projecting therefrom which is suitably connected by a universal joint, or the like, 30 to an actuating rod 31 which has an angular extension 32 and a return bend formation 33. The valve member 28 includes a chamber 34 and includes a port 35 communicating therewith and which is adapted to alternately register with the passage 37 in the valve body 26, which is in free communication with the compartment 19, and to register with the passage 38 in free communication with the upper portion of conduit 25 that is in free communication with the boiler 22.

The numeral 39 indicates generally a standard form of heating device which is positioned directly beneath the flash boiler 22 and the heat from the former heats the lower surface of the latter and all the other surfaces, and then passes upwardly along the bottom and sides of the two cylindrical compartments, being retained between said bottom and sides and the shields 20, before mentioned. Thus, after the heat is utilized for boiler heating purposes, the heat is utilized to heat the water in the compartment 19 which is the clear water supply, and the water in the compartment 18, which is the supply for can washing.

When the handle 32—33 is turned approximately 180° from the position shown in Fig. 2, then the water which previously has flowed into the valve chamber 34, is discharged into the flash boiler and the remaining water in compartment 19 is cut off from flowing into the boiler and the steam cannot discharge to compartment 19. The valve chamber 34 when positioned as shown in

Fig. 2, thus will always be full as long as there is water to the level of the intake of the valve in the compartment 19. Thus, only the measured amount of water, to-wit; that received by the valve chamber 34, will be discharged to the flash boiler for the generation of steam.

Compartment 19 may be closed by a hinged lid structure 40. Compartment 18 is provided with an outlet 41 terminating in a valve 42 by which said compartment 18 may be drained. Compartment 19 is provided with an outlet 43 and the conduit 44 terminates in a valve 45 by which the compartment 19 may be drained.

The boiler, as stated, discharges generated steam by way of conduit 23 which is connected to a T fitting 46, one outlet thereof being closed by plug 47, the latter constituting a drain. The other outlet is connected by the angular line 48 to a riser 49 terminating in a nozzle or tip 50 of any preferred or desired design.

A ring 51 is suitably supported by the downwardly inclined straps or brace members 52, riveted or otherwise secured as at 53—see Fig. 3—to the legs 11 and riveted or otherwise secured 25 to the ring member 51 as at 54. Another pair of brace members 55 is also secured to the ring as at 54 and also secured to the ring as at 56, the other end being suitably secured to the angle iron framework as at 57. A tubular spacing member 58 is suitably secured to the ring as at 59 and to the angle iron frame member 10 as at 60. This may be of a bolt and nut type, if desired, the bolt extending through the tubular member 58. Thus, the ring is rigid with 35 the machine frame, and at one side thereof.

A frusto conical funnel or drain member 61 terminates in a beaded edge 62 in which is mounted a reenforcing member or wire 63—see Fig. 1. The lower coaxial edge includes the 40 orifice 64 which is coaxial with the riser 49.

Extending through the funnel or drain is a pair of bars or rods 65, the same being positioned in a plane tangent to the lowest surface of the bead of the funnel and being soldered or otherwise suitably secured to the funnel as at 66. The ring is notched as at 67 at opposite sides to nest said rods, where the same project outwardly beyond the exterior lower surface of the funnel at opposite sides thereof. The rods 50 at one side and the side which is to be positioned adjacent the machine frame are extended as at 68 and the same are adapted to lie immediately beneath the outwardly directed flange of the frame member 10.

The spacing of the two rods 65 is such that a cream can mouth will bear on both rods and be supported thereby for supporting the cream can in inverted position.

The purpose of the cover 40 is to permit the 60 transfer of the cream can from its inverted position shown to the left in Fig. 1 to its side position shown to the right in Fig. 1 and then back to the first position without drippings falling into clean water compartment 19.

The operation of the device is as follows:

Clean water is supplied to compartments 18 and 19 in any suitable manner. The heating device 39 is ignited and when the boiler has attained the proper heat, the water in the two 70 compartments will also be heated. Then a cream can is inverted and is positioned on the rods 65 with the nozzle inside the can. The valve 29 is then operated to supply a measured amount of water to the flash boiler which is immediately 75 generated into steam and discharges through

the nozzle 50 into the cream can and this steam is sprayed into the can and then the condensed steam together with what cream and butter fat adheres to the can sides and bottom runs down and drains from the can into the conical drain 61 and thence collects in the can 70, shown dotted in Fig. 1, and positioned in registration with the opening 64 of said drain.

Following this operation, the can is removed from the bars 65, placed in compartment 18 and rotated therein to wash the exterior and the interior of the can. The can is removed from the compartment 18 and may be positioned to one side until the cream from all of the cans has been removed and the cans have been cleansed, or if desired, the can immediately after washing may be returned to its inverted position upon the bars 65, as shown in the upper left hand portion of Fig. 1, and then valve 29 is again operated to supply another injection of steam 20 to the can and this injection of steam sterilizes the can.

It will be obvious from the foregoing description that all of the cream may be readily removed from the same and the cans may be 25 expeditiously washed and sterilized. The valve structure is such that it is adapted to supply hot, clean water and in a measured amount to the flash boiler to generate steam.

Heretofore in devices of this general character, it has been the custom to supply cold water to the flash boiler which materially reduces the efficiency of the steam generation.

With the present invention, the supply of water for steam generation is of the gravity feed type and the supply of water is a measured amount, only that which may be trapped by the valve and transferred by the valve until it is discharged to the boiler. This invention has the advantage that the two compartments may be readily cleaned since they have semi-cylindrically shaped bottoms.

Furthermore, this invention has a very important advantage and that is that the conical drain is readily detachable from its support for 45 cleaning and sterilizing after the day's work has been done and for a similar operation previous to starting the day's work. All that is required is to elevate by tilting upwardly and toward the machine proper, the funnel arrangement so that the projecting portions of the bars 65 are removed from the several notches in the support ring and then tilting movement is continued further until the portions 68 of the bars, if projected upwardly, would clear the outer edge of 50 the flange of the frame member 10 and then the funnel is directly elevated for complete removal and subsequent washing.

The projecting portions 68 of the bars 65, it will be obvious, by nesting beneath the flange of 60 the angle iron 10, serve to prevent the escape or movement of the funnel when the bars are nested in the notches of the support ring. It will also be apparent—see Fig. 1—that the beaded edge 62 of the funnel or drain has substantially 65 full peripheral contact with the top edge of the support ring so that the funnel is relatively rigidly positioned when properly seated.

The angular arrangement 48 of the steam discharge connection to the riser and nozzle insures 70 clearance for the cream can 70 that receives the fat and cream which drain from the cans. After this operation, another can may be positioned beneath the opening 64 in the funnel and this can catches all the sterilizing condensate. The 75

diameter of the opening 64 is sufficiently large to permit the tilting of the conical drain or funnel for its subsequent separation from its support without interference from the riser 49.

5 While the invention has been set forth in great detail in the foregoing description and has been illustrated in similar detail, the same is to be considered as illustrative and not restrictive in character. Various modifications of the present disclosure will readily suggest themselves to persons skilled in this art and such modifications are all considered to be within the broad scope of this invention, reference being had to the appended claims.

15 The invention claimed is:—

1. In a can washer and sterilizer, the combination with a can washing device including a frame structure and a steam supply riser offset therefrom and supported thereby, of draining and can supporting means juxtaposed relative thereto and supported by the frame structure including a funnel, the riser extending upwardly therethrough, a support ring carried by the frame structure and peripherally and detachably supporting said funnel, and means through which the riser projects and positioned within the funnel for supporting a can in inverted relation, said last mentioned can support means projecting through the funnel and operatively engaging the frame structure for the purpose described.

2. In a can washer and sterilizer, the combination with a can washing device including a frame structure and a steam supply riser offset therefrom and supported thereby, of draining and can supporting means juxtaposed relative thereto and supported by the frame structure including a funnel, the riser extending upwardly therethrough, a support ring carried by the frame structure and peripherally and detachably supporting said funnel, and means through which the riser projects and positioned within the funnel for supporting a can in inverted relation, said ring nestably receiving said funnel and the latter having a beaded edge contacting the upper surface of the ring when the funnel is nested therein.

3. In a can washer and sterilizer, the combination with a can washing device including a frame structure and a steam supply riser offset therefrom and supported thereby, of draining and can supporting means juxtaposed relative thereto and supported by the frame structure including a funnel, the riser extending upwardly therethrough, a support ring carried by the frame structure and peripherally and detachably supporting said funnel, means through which the riser projects and positioned within the funnel for supporting a can in inverted relation, said ring nestably receiving said funnel, and spaced means projecting from the lower exterior side of said funnel and operatively seating upon the ring.

4. In a can washer and sterilizer, the combination with a can washing device including a frame structure and a steam supply riser offset therefrom and supported thereby, of draining and can supporting means juxtaposed relative thereto and supported by the frame structure including a funnel, the riser extending upwardly therethrough, a support ring carried by the frame structure and peripherally and detachably supporting said funnel, means through which the riser projects and positioned within the funnel for supporting a can in inverted relation, said ring nestably receiving said funnel, and spaced

means projecting from the lower exterior side of said funnel and operatively seating upon the ring, said ring being notched to seat said spaced means.

5. In a can washer and sterilizer, the combination with a can washing device including a frame structure and a steam supply riser offset therefrom and supported thereby, of draining and can supporting means juxtaposed relative thereto and supported by the frame structure including a funnel, the riser extending upwardly therethrough, a support ring carried by the frame structure and peripherally and detachably supporting said funnel, means through which the riser projects and positioned within the funnel for supporting a can in inverted relation, said ring nestably receiving said funnel, and spaced means projecting from the lower exterior side of said funnel and operatively seating upon the ring, said ring being notched to seat said spaced means, said ring having a beaded edge peripherally contacting the upper surface of said ring when the funnel is nested therein.

6. In a can washer and sterilizer, the combination with a can washing device including a frame structure and a steam supply riser offset therefrom and supported thereby, of draining and can supporting means juxtaposed relative thereto and supported by the frame structure including a funnel, the riser extending upwardly therethrough, a support ring carried by the frame structure and peripherally and detachably supporting said funnel, a pair of spaced bars extending across the funnel and between which the riser projects, said bars projecting through and beyond the funnel, said ring including registering notches for seating said bar projecting ends.

7. In a can washer and sterilizer, the combination with a can washing device including a frame structure and a steam supply riser offset therefrom and supported thereby, of draining and can supporting means juxtaposed relative thereto and supported by the frame structure including a funnel, the riser extending upwardly therethrough, a support ring carried by the frame structure and peripherally and detachably supporting said funnel, a pair of spaced bars extending across the funnel and between which the riser projects, said bars projecting through and beyond the funnel, said ring including registering notches for seating said bar projecting ends, the rim of the funnel being beaded and the beading resting upon the upper surface of the ring.

8. In a can washer and sterilizer, the combination with a can washing device including a frame structure and a steam supply riser offset therefrom and supported thereby, of draining and can supporting means juxtaposed relative thereto and supported by the frame structure including a funnel, the riser extending upwardly therethrough, a support ring carried by the frame structure and peripherally and detachably supporting said funnel, a pair of spaced bars extending across the funnel and between which the riser projects, said bars projecting through and beyond the funnel, said ring including registering notches for seating said bar projecting ends, the bars being directed longitudinally toward the frame structure and terminating, when seated in the notches, immediately adjacent an overhanging edge thereof for the purpose described.

9. In a can washer and sterilizer, the combina-

- 5   tion with a can washing device including a frame structure and a steam supply riser offset therefrom and supported thereby, of draining and can supporting means juxtaposed relative thereto and supported by the frame structure including a funnel, the riser extending upwardly therethrough, a support ring carried by the frame structure and peripherally and detachably supporting said funnel, a pair of spaced bars extending across the funnel and between which the riser projects, said bars projecting through and beyond the funnel, said ring including registering notches for seating said bar projecting ends, the bars being directed longitudinally toward the frame structure and terminating, when seated in the notches, immediately adjacent an overhanging edge thereof for the purpose described, the rim of the funnel being beaded and the beading resting upon the upper surface of the ring.
- 10   10. In a can washer and sterilizer, the combination with a can washing device including a frame structure and a steam supply riser offset therefrom and supported thereby, of draining

and can supporting means juxtaposed relative thereto and supported by the frame structure including a funnel, the riser extending upwardly therethrough, a support ring carried by the frame structure and peripherally and detachably supporting said funnel, a pair of spaced bars extending across the funnel and between which the riser projects, said bars projecting through and beyond the funnel, said ring including registering notches for seating said bar projecting ends, the bars being directed longitudinally toward the frame structure and terminating, when seated in the notches, immediately adjacent an overhanging edge thereof for the purpose described, the funnel outlet or 15 mouth being of appreciable area to permit tilting of the funnel without riser interference for detachment of the funnel, said riser immediately below the plane of the mouth having a lateral portion for drain can clearance and directed to- 20 ward the frame structure.

FREDRICK W. COFFING.
